(57) **CLAIM**

The ornamental design for a handlebar with an adjustable stem for scooters, as shown and described.

DESCRIPTION

The patent or application file contains at least one drawing executed in color. Copies of this patent or patent application publication with color drawing(s) will be provided by the Office upon request and payment of the necessary fee.

1. Handlebar with adjustable stem for scooters

1.1 : Front

1.2 : Back

1.3 : Left

1.4 : Right

1.5 : Top

1.6 : Bottom

1.7 : First Perspective View

1.8 : Second Perspective View

The red-colored portions indicate portions of the handlebar with adjustable stem for scooters that form no part of the claimed design.
